DISPLAY RACK OR THE LIKE

James A. Engelmann, Highland Park, Ill., assignor to Paper Mate Manufacturing Company, Culver City,
Calif., a corporation of Delaware

Application April 16, 1957, Serial No. 45,748

Term of patent 14 years

(Cl. D80—9)

Fig. 2 is a view in front elevation thereof;

Fig. 3 is a view in side elevation thereof;

Fig. 4 is a view in top plan; and

Fig. 5 is an enlarged fragmentary vertical sectional view taken in the plane indicated by line 5—5.

I claim:

The ornamental design for a display rack or the like, as shown.
